UNITED STATES PATENT OFFICE.

JOSEPH A. GROEBLI, OF NEW YORK, N. Y., ASSIGNOR TO THE KURSHEEDT MANUFACTURING COMPANY, OF NEW YORK, N. Y., A CORPORATION OF NEW YORK.

BORE MECHANISM FOR EMBROIDERING-MACHINES.

No. 902,817.

Specification of Letters Patent.

Patented Nov. 3, 1908.

Application filed February 21, 1907. Serial No. 358,736.

To all whom it may concern:

Be it known that I, JOSEPH A. GROEBLI, a citizen of the United States, residing at New York city, in the county of New York and State of New York, have invented new and useful Improvements in Bore Mechanism for Embroidering - Machines, of which the following is a specification.

My invention relates to boring mechanism for embroidery machines within which term I desire to include any and all mechanism for perforating or piercing devices which will make holes in the fabric stretched upon the fabric frame of an embroidery machine.

It will be readily understood that the boring mechanism is designed primarily to operate in conjunction with needle-mechanism to produce embroidery. The stitch forming mechanism is not shown in the drawings.

In the accompanying drawings, I have shown one specific form of apparatus having as its object to throw the bore points into action with certainty in an indirect manner and to regulate their stroke without the necessity of positioning the bore points as is done in the mechanism shown in U. S. Letters Patent No. 593,207, dated Nov. 9, 1897 and issued to The Kursheedt Manufacturing Co. as my assignee.

In these drawings:—Figure 1 is a side elevation of one form of mechanism embodying my invention; Fig. 2 is an end elevation thereof; Fig. 3 is a side elevation of the adjuster 40 hereinafter referred to with borer actuating rod dotted in; Fig. 4 is a section thereof showing the borer actuating rod in full lines; Fig. 5 is a perspective view of a frame or lever 25 which, among other things, serves the function of operating the adjuster; Fig. 6 is a side view of the actuating lever 11, for the bore point actuating rod; Fig. 7 is a plan view thereof, partly broken away to show the bowl 16, and its moving pin 17; Fig. 8 is a perspective of an arm 21 which inserts the bowl 16 of the arm 11, into its cam; Fig. 9 is a face view of the cam 31 which rocks the frame 25; Fig. 10 is a side view of a fixed piece 37, for receiving the bowl and holding it stationary when the bowl is not in operation and holding it up to the work when the bowl is in operation.

In the drawing A indicates in general the frame of the embroidery machine forming the main support for the parts. The borers

1 are carried preferably upon a common bar 2 carried by the usual reciprocating rods or slides 3 working in bearings 4. The rods 3 are pivoted to a bell crank-lever 5 pivoted at 6 on the frame of the machine. The lower 60 or free end of the lever 5 is pivotally connected to the upper end of the bore-point actuating rod 7 whose lower end is provided with a pin 8 having a faceted or squared end 9, see Fig. 4.

The rounded portion 8 of the pin is adapted to enter a series of holes 10 in the arm 11 being located at the bottom of a counter-sink portion 12 so that the pin 8 will not leave the arm while it is being adjusted along the said arm as will be explained. The arm 11 is pivoted to the frame A at 13 and has at or near its free end a sleeve 14 slotted at 15 (see Fig. 2) for a portion of its length and adapted to 75 receive a bowl 16 having a pin 17 projecting therefrom through the slot 15 in the sleeve 14.

The bowl 16 is adapted to be entered at predetermined times into the cam slot 18 in 80 the cam 19 carried on the shaft 20 supported from the frame of the machine. This movement may be effected as follows; A normally idle swinging arm 21 is hung on the stud or support 22 and is provided at one end 23 85 with a cam slot 23^a into which the pin 17 enters. The cam slot 23^a is open at 23^b to allow the pin 17 to pass out of the slot. At its opposite end the arm 21 has a slot 24 formed by jaws 24^a between which a pin is 90 adapted to rest. Carried on the stud or support is a bent lever or frame 25 comprising an arm 26 having a slot 27 therein and an arm 28 having a bowl or piece 29 working in a cam slot 30 and imparting to the arm or frame 25 a constant swing. Adapted to cooperate with and enter the slots 24 and 27 in the arms 21 and 29 to couple them to swing together is a pin 32 adapted to enter locking apertures 33 in the main frame on its return 100 stroke. The pin 32 is moved and controlled by a jacquard or pattern connection 34 herein shown as actuated through a lever 35 by a lifter k^a of a series of lifters of the jacquard J clearly shown in my Letters Patent 105 No. 528,632, dated Nov. 6, 1894.

In order to maintain the bowl 16 in a normal position of rest when desired and to hold it up to the work when it is in operation I may provide a fixed locking and retaining 110

piece 37 which is fast upon the stud or bar 22. This locking piece is provided with a jaw-bounded recess 37^a and an arm 37^b. When the bowl 16 is in its position of rest its outer end is entered into the recess 37^a and held from swinging movement. It is, however, free to slide to leave the locking piece and enter the cam 18. It may, however, be found desirable to alter the extent of stroke of the borers. This may be done as follows: The holes 10 in the arm 11 are at different distances from the center of swing of the arm. By shifting the lower end of the rod 7 along the arm 11, and entering its pin 8 into any desired hole 10 the stroke of the borers may be varied without preliminarily positioning them for action. This may be accomplished by the adjusting mechanism which may be constructed as follows: A pin 38 is carried on the constantly moving arm 26 and is pivotally connected to a link 39 which is secured to or may be said to form part of the adjuster 40. This adjuster slides horizontally in response to the movement of the link 39 and is provided with a set of jaws 40^a fitting over a guide stud 40^b. The adjuster is provided with a set of rigid teeth 40^c and swinging end teeth 40^d to prevent breakage upon any unusual accidental movement of the lower end of the rod 7. The rod 7 is provided with a stirrup 41 into which enters a plate 42 connected to a jacquard or pattern connection 43 extending to a jacquard or pattern element *k*^o. The pin 8 at the lower end of the rod 7 normally extends to the bottom of the recess 12 in the arm 11 and enters one of the holes 10 in said arm: Suppose it is desired to shift it two holes. The jacquard goes into action and pulls the pin 8 from its hole 10 (but not far enough to clear it of the recess 12) and enters its squared portion 9 into one of the spaces between the teeth 40^c of the adjuster 40. This occurs during a pause in the reciprocation of the adjuster (see cam Fig. 9). The adjuster moves forward one hole space and the pin is withdrawn by the jacquard and entered into the arm 11. The adjuster slides a step in the other direction and the pin is again entered therein and moved another step and entered into the proper hole in the arm 11. The jacquard connection 43 then remains idle until the next adjustment is to be effected.

The detailed operation will be understood from the foregoing description. It may be described as follows: The adjusting apparatus may be put into action by the pattern mechanism several stitch periods in advance of the bore-point operating mechanism. This apparatus operates in a sense independently of the bore-point moving mechanism by which for the purposes of this case only I mean the mechanism for moving the rod 7 to bring about the boring oper-

ation. It also operates in a sense independently of the positioning mechanism for the bore-point operating mechanism, by which for the purposes of this case only, I mean that mechanism by which the bowl is entered into the cam without any positioning movement of the bore-points. The jacquard forms the connecting link between these mechanisms in one sense and their direct connections with each other constitute connections in another sense so that they are at different times independent and interdependent. The positioning mechanism may now be thrown into action by the jacquard device coupling the levers 21 and 26 by the pin 32. This will by pin and slot connection, 17, 23^a move the bowl 16 out of the slot 37^a in the piece 37 and insert it into the cam slot 30 of the cam 31 by which it is moved to operate the borers. The rear end of the bowl 16 is kept up to its work, *i. e.* in the cam 31, by the arm 37^b on the arm 37. The pin 32 is withdrawn by the jacquard and the boring continues until it is desired to stop the boring when the pin 32 is again engaged with the levers 21 and 26 when 21 is on its back stroke and the parts are restored to their normal positions.

In my present device the borers are normally in such a position that they may be operated without any change, that is to say they are simply advanced into the fabric and a primary positioning action is not necessary as is the case in my U. S. Patent No. 593207. By the present arrangement the jacquard positively connects the bore mechanism for immediate action and it remains in operation as long as desired without having to be positioned during the operations. The jacquard, when the boring is completed, simply uncouples the bore mechanism and the bore mechanism remains where it is left. This coupling of the mechanism for immediate action is not effected by the change in the adjustment for advancing the operations of the borers.

Having described my invention, what I claim and desire to secure by Letters Patent is:—

1. In an embroidering machine, the combination of bore mechanism having bore points, operating mechanism for operating the bore mechanism, an adjustable connection in the bore mechanism for altering the stroke of the bore points, a movable member adapted to operate said bore stroke adjusting device and adapted to connect the operating mechanism with the bore mechanism and a pattern mechanism independently controlling the connecting of the operating mechanism with the bore mechanism and the operation of the said bore stroke adjusting mechanism.

2. In an embroidering machine, the combination of bore mechanism having bore

points, operating means for operating the bore mechanism, a coupling device for coupling the operating means and bore mechanism, an adjusting device for adjusting the 5 stroke of the bore points and a common means for operating the said adjusting device and the said coupling device.

3. In an embroidering machine, the combination of bore mechanism having bore 10 points, operating means for the bore mechanism, a coupling device for coupling the bore mechanism and operating means, an adjusting device for adjusting the stroke of the bore points, a common means for operating 15 the said adjusting device and the said coupling device and pattern mechanism for independently controlling the action of the said adjusting device and the said coupling device.

20 4. In an embroidering machine, the combination of bore mechanism having bore points, normally inactive, a source of power, a coupling device adapted to couple the bore mechanism with the source of power, 25 a movable element continually operated by the source of power, means whereby said movable element may be connected with said coupling device to operate the latter and means for operating the same.

30 5. In an embroidering machine the combination of bore mechanism having bore points, normally inactive, a source of power, a cam operated thereby and an oscillating member continually operated by the source 35 of power, a normally stationary member adapted to effect a coupling of the bore mechanism and cam and means for connecting said oscillating member and said bore coupling member to cause the operation of 40 the latter.

6. In an embroidering machine the combination of bore mechanism having bore points, normally inactive, a source of power, a cam operated thereby, and an oscillating 45 member continuously operated by the source of power, a normally stationary member adapted to effect a coupling of the bore mechanism and cam, a pattern mechanism and means operated by the pattern mechanism adapted to connect said oscillating member and said bore coupling member, to cause 50 the operation of the latter.

7. In an embroidering machine the combination of a source of power, a moving part 55 continually operated by the source of power, an operating element of the embroidering machine, operating means for said element comprised in part by a bowl and a cam adapted to engage the bowl, means adapted 60 to be coupled with said moving part and adapted to engage the bowl with said cam and means for effecting the coupling of the bowl coupler and moving part.

8. In an embroidering machine, the combination of a normally moving part, an op- 65

erating element of the embroidering machine, operating means for the said operating element comprised in part by a cam and shiftable bowl, means for shifting the bowl and means for coupling, the last named 70 means with the normally moving part at predetermined times, adjusting means for altering the stroke of the said operating element operated from the normally moving part and pattern mechanism for controlling 75 the action of the adjusting means.

9. In an embroidering machine, the combination of a normally moving part, an operating element of the embroidering machine, operating means for the said operating element comprised in part by a cam and shiftable bowl, means for shifting the bowl and means for coupling, the last named 80 means with the normally moving part at predetermined times, comprised in part by 85 a shiftable pin and engaging the normally moving part and the coupling means to couple the same together.

10. The combination in an embroidering machine of bore-points, operating mechanism therefor, an adjusting means for adjusting the stroke of the bore points, means for operating the adjusting means, and means for controlling a part of the operating means comprising a plurality of levers, means for 95 normally moving one of the said levers and means for coupling the levers.

11. The combination in an embroidering machine of bore-points, operating mechanism therefor, an adjusting means for adjusting 100 the stroke of the bore points, means for operating the adjusting means, means for controlling a part of the operating means comprising a plurality of levers, means for normally moving one of the said levers and 105 means for coupling the levers, and pattern mechanism for controlling the operation of the adjusting means.

12. In an embroidering machine, the combination of bore mechanism having bore 110 points and provided with a lever, a source of power adapted to operate said lever, a normally moving lever, means for adjusting the stroke of said bore points operated by said normally moving lever, a normally station- 115 ary lever adapted to cause the said bore mechanism lever to be operatively connected with the source of power and means for connecting the normally moving lever and the normally stationary lever to cause the opera- 120 tion of the latter.

13. In an embroidering machine, the combination of an element of the embroidering machine, operating means therefor, comprised in part by a movable device, a nor- 125 mally stationary part for shifting the movable device to couple the operating device for action, an adjusting device to determine the action of the operating device, a nor- 130 mally moving part connected to the adjust-

ing device, and means for connecting the normally moving device and the normally stationary device for joint action.

14. In an embroidering machine the combination of a pattern mechanism, bore points and operating mechanism therefor, embodying a cam and a lever having a bowl adapted to be operated thereby, a continually moving member changing to alternate positions, means for coupling and uncoupling said bowl with the said cam and means operated by the pattern mechanism for connecting

said bowl coupling means with said continually moving member in its several positions to effect the coupling or uncoupling of the 15 bowl with the said cam.

Signed at New York City, county of New York, and State of New York, this 20th day of February 1907.

JOSEPH A. GROEBLI.
